Primary Examiner — Jack Reickel*Assistant Examiner* — Michael A Kervin(74) *Attorney, Agent, or Firm* — Fitch, Even, Tabin & Flannery LLP(57) **CLAIM**

The ornamental design for a hanger, as shown and described.

DESCRIPTION

FIG. 1 is a top perspective view of a hanger in accordance with my new design;

FIG. 2 is a top plan of the design of FIG. 1;

FIG. 3 is a bottom plan view of the design of FIG. 1;

FIG. 4 is a left side elevation view of the design of FIG. 1;

FIG. 5 is a right side elevation view of the design of FIG. 1;

FIG. 6 is a front elevation view of the design of FIG. 1; and,

FIG. 7 is a rear elevation view of the design of FIG. 1.

The broken line showing of a hanger is for the purpose of illustrating portions of the article and forms no part of the claimed design.
